UNITED STATES PATENT OFFICE.

EDWARD PAUL TOURNIER, OF CHICAGO, ILLINOIS, ASSIGNOR TO WESTERN ELECTRIC COMPANY, INCORPORATED, OF NEW YORK, N. Y. A CORPORATION OF NEW YORK.

TOOL.

Application filed April 17, 1925. Serial No. 23,861.

This invention relates to tools, and more particularly to a tool for handling U-shaped elements and has for its primary object a simple and inexpensive tool for readily and efficiently attaching and detaching different sizes of resilient clips or clamping members of the type disclosed and claimed in co-pending application of G. J. Houts, Serial No. 745,093, filed October 22, 1924.

As mentioned above the invention relates to tools for attaching or detaching U-shaped clips for securing strands to a support and in accordance with the general features thereof, there is provided in one embodiment thereof a lever, which is provided with a grooved surface for guiding the portion connecting the side portions of a U-shaped clip while attaching it to or detaching it from a support, the opposite end of the lever being fulcrumed upon an adjustable member with a hook like portion for engaging the support. The member is normally maintained in an engaging position and a projecting member engaging the strands within the clip serves as a guide or stop in positioning the tool.

Other objects and advantages of the invention will more fully appear from the following detailed description taken in connection with the accompanying drawings which illustrate one embodiment thereof, and in which

Fig. 1 is a perspective view of a tool embodying the features of the invention, showing one manner in which it may be used when fastening telephone switchboard cables to a supporting frame;

Fig. 2 is an enlarged plan view thereof, and

Fig. 3 is a vertical end view looking toward the left hand side of Fig. 2.

The invention herein illustrated and described is particularly applicable for use in attaching to, or detaching from supporting frames, strand clamping members or clips, especially those embracing telephone switchboard cables, by the method disclosed in the co-pending application hereinbefore referred to, but it is to be understood that the novel features of the invention are capable of other applications.

Referring to the drawings wherein like reference numerals designate like parts throughout the several views, 10 indicates a bar or lever provided at one end with an

angularly disposed portion 11 forming a handle for the tool. The work engaging face of the lever 10 is provided with a plurality of grooves 12 within one or the other of which a resilient portion 13 of a clamping member or clip 14 is entered when positioning the tool preparatory to mounting the clip upon its supporting member. The clip 14 illustrated in Fig. 1 is of a type substantially like that disclosed in several different forms in the hereinbefore mentioned application to which reference may be had for a more detailed description thereof. The lever 10 at its right hand end is bifurcated in a longitudinal direction as indicated at 17 and between the arms 18 of the bifurcation and pivotally supported upon a shoddered screw 19 threaded into one of the arms 18 is a member 20, the screw 19 forming the fulcrum for the lever. The member 20 is provided with two separated openings 21 either of which may be used for the screw 19 whereby the working portion of the member 20 may be readily adjusted upon the lever 10 to provide for different sizes of clips as will be more fully set forth hereinafter. The member 20 is provided with a hook like portion 22 at one end for engaging the supporting framework to which the clip 14 is to be attached or detached from, as clearly shown in Fig. 1. The hook like portion 22 comprises a right angle extension 23 terminating at its end in a portion 24 extending parallel to the main portion of the member 20. The member 20 is normally urged clockwise about the fulcrum of the lever for convenience in mounting the tool, by the engagement of the free end of a leaf spring 26 secured to the underside of the lever 10, as indicated at 27 (Fig. 1), with the free end of the spring 26 extending upwardly through the bifurcation 17 and engaging the left hand face of the member 20. For the purpose of guiding the tool into position with respect to the strands being clamped, in the present instance telephone switchboard cables, the upper face of the lever 10 at one side has suitably secured thereto a projecting guide 28 comprising a length of wire formed into a loop.

The operation of this tool is as follows:

Referring to Fig. 1 wherein a telephone switchboard cable assembly is shown, 30 indicates a plurality of cables being clamped to a channel member 31 extending trans-

versely of the length of the cables by the clamping member or clip 14 having bent or hooked portions 33 at opposite ends which are adapted to be hooked over surface 34 of the channel 31. The cable assembly illustrated in Fig. 1 consists of two vertical rows, with five cables in each row, but it will readily be understood that when clamping a row of three cables for instance, the working end 10 of the member 20 should be shortened. This may be accomplished by fulcruming the lever 10 to the member at the free opening 21. In using the tool the operator first positions a clip 14 around the cables 30 adjacent 15 the closed face of the channel 31 and with one hooked portion engaging the top surface of the channel. The hook portion 22 of the member 20 is then also engaged with the upper surface of the channel 31 and substantially at the same instant the guide 28 20 engages the cables as shown in Fig. 1, in case the tool is properly positioned the portion 13 of the clip being entered in one or the other of the grooves 12. In case the tool is 25 not properly positioned with respect to the clip, it is moved along the channel member until the guide 28 engages the cables, as shown. In this position the clip 14 will be securely held between the lever 10 and the 30 cables and thereafter by pulling upwardly upon the handle 11, the lever fulcruming upon the screw 19, the cables will be lifted and compressed until the hook portion 33 of the clip rises above the channel member 35 31, whereupon the operator may move the hooked end over the upper surface 34 of the channel until it will move downwardly and firmly rest upon the channel in its engaging position as shown at the left hand end of 40 Fig. 1. To disengage a clip 14 from the channel the operator merely mounts the tool as described hereinbefore and pulls upwardly upon the handle thereby raising the hook portion 33 to a point where it may be 45 disengaged from the surface 34 of the channel by moving it transversely thereacross.

In Fig. 1 the cables 30 are shown as suspended from the channel 31 but it is sometimes convenient and frequently necessary 50 to support and secure the cables upon the upper face of the channel member or to arrange the cables in vertical assemblies fastened to suitable supports and it will be readily apparent that the tool hereinbefore 55 described may be used equally well for such purposes.

From the foregoing description it will be seen that the tool described is of comparatively simple formation in its construction and the arrangement of its parts and that it can be manipulated with very little skill on the part of an operator. It will be clearly understood that the tool can be used for different types of clamping members for

different purposes, although particularly devised and illustrated in the drawings for use in attaching or detaching the clips used in the method disclosed in the hereinbefore mentioned patent.

What is claimed is:

1. A tool comprising a lever adapted to engage and guide an element to operatively engage a support therefor, a member providing a fulcrum point for the lever and having a portion for operatively engaging the said support, and means for normally holding said member in a predetermined position relative to the lever.

2. A tool comprising a lever adapted to engage an element, a member providing a fulcrum for the lever and adapted to operatively engage a support, and resilient means associated with said member for normally holding said member in a predetermined position relative to the lever.

3. A tool comprising a lever adapted to engage an element, a member adapted for adjustment thereon for different sizes of elements and providing a plurality of fulcrum points for the lever, said member adapted to operatively engage a support, and resilient means for normally holding said member in a predetermined position relative to the support.

4. A tool comprising a lever adapted to engage an element containing a strand, a stop member carried thereby for engaging the strand and thereby positioning the lever, and a connecting link providing a fulcrum point for the lever adapted to operatively engage a support.

5. A tool comprising a lever provided with a plurality of depressed surfaces for guiding and retaining the intermediate portion connecting the side portions of a U-shaped element in engagement therewith, and a member providing a fulcrum point for the lever having a transversely extending hook portion for operatively engaging a support.

6. A tool comprising a lever adapted to engage and guide an element containing a strand to operatively engage a support therefor, a stop member carried thereby for engaging the strand and thereby positioning the lever, a link adapted for adjustment thereon for different sizes of elements and providing a plurality of fulcrum points for the lever, said link having a transversely extending hook portion for operatively engaging the said support, and resilient means fixed to said lever and bearing against said link for normally holding said link in a predetermined position relative to the lever.

In witness whereof, I hereunto subscribe my name this 10th day of April A. D., 1925.

EDWARD PAUL TOURNIER.
